UNITED STATES PATENT OFFICE.

RALPH F. CHATILLON, OF GREENBURG, NEW YORK.

DESIGN FOR A SCALE-BEAM WEIGHT.

45,370.

Specification for Design.

Patented Mar. 10, 1914.

Application filed April 16, 1912. Serial No. 691,220. Term of patent 14 years.

To all whom it may concern:

Be it known that I, RALPH F. CHATILLON, a citizen of the United States, residing at Greenburg, in the county of Westchester and State of New York, have invented a new, original, and ornamental Design for a Scale-Beam Weight, of which the following is a specification, reference being had to the accompanying drawing, forming part thereof.

Figure 1 is an elevation of a scale beam weight showing my new design, and Fig. 2 is a plan view.

I claim:

The ornamental design for a scale beam weight, as shown.

RALPH F. CHATILLON.
